(57) **CLAIM**

The ornamental design for a narrow profile condensing unit, as shown and described.

DESCRIPTION

FIG. 1 is a perspective view of the narrow profile condensing unit, showing my design;

FIG. 2 is a front elevational view of the my narrow profile condensing unit of my design;

FIG. 3 is a back elevational view of the narrow profile condensing unit of my design;

FIG. 4 is a left side elevational view of the narrow profile condensing unit of my design;

FIG. 5 is a right side elevational view of the narrow profile condensing unit of my design;

FIG. 6 is a top elevational view of the narrow profile condensing unit of my design; and,

FIG. 7 is a bottom elevational view of the narrow profile condensing unit of my design.

The broken lines in the drawings illustrate portions of the narrow profile condensing unit which form no part of the claimed design.
